(57) **CLAIM**

The ornamental design for a display screen with a graphical user interface, as shown.

DESCRIPTION

FIG. 1 depicts a front view of a display screen with a graphical user interface;

FIG. 2 depicts a front view of a display screen with a graphical user interface;

FIG. 3 depicts a front view of a display screen with a graphical user interface;

FIG. 4 depicts a front view of a first image in a sequence for a transitional image for a display screen with a graphical user interface;

FIG. 5 depicts a second image thereof; and,

FIG. 6 depicts a third image thereof.

The appearance of the transitional image depicted in FIGS. 4-6 sequentially transitions between the images shown in FIGS. 4-6. The process or period in which one image transitions to another forms no part of the claimed design. The features shown in broken lines depict environmental subject matter only (e.g., icons on the display screen) and form no part of the claimed design.
